Specification for Design.

Patented Aug. 26, 1913.

Application filed October 19, 1912. Serial No. 726,817. Term of patent 14 years.

To all whom it may concern:

Be it known that I, ARTHUR J. STOBBART, a citizen of the United States, residing at St. Paul, in the county of Ramsey and State of Minnesota, have invented a new, original, and ornamental Design for a Buckle-Plate for Uniform-Belts, of which the following is a specification, reference being had to the accompanying drawing, forming a part thereof.

The accompanying drawing, illustrating

my design, shows the face of a buckle plate for uniform belts embodying the same.

I claim:

The ornamental design for a buckle plate for uniform belts, as shown.

In testimony whereof I affix my signature in presence of two witnesses.

ARTHUR J. STOBBART.

Witnesses:

H. SWANSON,

H. S. JOHNSON.
